UNITED STATES PATENT OFFICE.

JAMES BETTNEY, OF NOTTINGHAM, ENGLAND.

THICKENING MECHANISM FOR CIRCULAR-KNITTING MACHINES.

SPECIFICATION forming part of Letters Patent No. 451,747, dated May 5, 1891.

Application filed July 1, 1890. Serial No. 357,360. (No model.) Patented in England November 5, 1889, No. 17,622.

To all whom it may concern:

Be it known that I, JAMES BETTNEY, machinist, a subject of the Queen of Great Britain, residing at 66 Robbinhood Street, Nottingham, England, have invented certain Improved Thickening Mechanism for Circular-Knitting Machines, (for which I have obtained a patent in Great Britain, No. 17,622, bearing date November 5, 1889,) of which the following is a specification.

This invention relates to circular hosiery knitting machines; and it consists of certain new and useful additions to the feed mechanism for enabling the operative to work an additional thread into the material where necessary, such additional thread being carried to and worked into the material together with the ordinary thread, whereby certain parts of the material can be thickened by the process commonly known as "splicing."

In order that my said invention may be particularly described and ascertained, reference is hereby made to the accompanying drawings, in which similar letters of reference indicate corresponding parts.

Figure 1 is a plan of a portion of a circular hosiery knitting machine fitted with my additional mechanism. Fig. 2 is a plan of another portion of the same. Fig. 3 is an elevation, partly in section, showing the carrier, the bolt for working the same, and its connection with the cylinder and cam-plate. Fig. 4 is a side view, and Fig. 5 an edge view, of the carrier. Fig. 6 is an elevation of the lever for operating the shear-blade for cutting the additional thread. Fig. 7 is an elevation of the catch and spring, with sections of portions of the cylinder and cam-plate for connecting and disconnecting the thickening mechanism. Fig. 8 is a diagram taken at right angles to the looper-wheel, showing the relative positions of the thread-guide, shear-blade, and looper-wheel. Fig. 9 is a diagram taken at right angles to Fig. 8. Fig. 10 is a section of the looper-wheel, showing the particular form of one of the wings for seizing the additional thread which forms the thickening of the material and passing such additional thread on to the needles.

Referring to Figs. 1 to 5, *a* is a bracket bolted to the bed-plate *b*. *a'* and *a²* are stationary sockets attached to or forming part

of the bracket *a*. These sockets act as guides to the vertical reciprocating bolt *c*. *c'* is an adjustable collar secured to the bolt *c* by a screw *c²*. This collar receives the upward thrust of the spiral spring *d*, whereby the bolt *c* is constantly pressed upward. The lower end of the bolt *c* is fitted with a roller-truck *e*, the roller working on a pin *e'*. *f* is the carrier-arm for conveying the additional thread for thickening. This carrier consists of a vibrating lever pivoted to the upper end of the bolt *c* at *f'*. Fig. 4 is a separate view of the carrier *f*, and Fig. 5 is a plan of the same. *f²* is a movable plate, which slides in the slot formed in the carrier to receive the pin *a⁴*. This pin *a⁴* is riveted to the plate *a³*, and the plate *a³* is secured to the bracket *a* by a screw *a⁵*, as shown in Figs. 1 and 3.

Referring to Figs. 1, 6, and 7, *g* is the cylinder, to which the needles *g'* are fitted in the usual manner. *h* is a cam-plate having flanges, cams, or thickened portions *h'* and *h²*. The cam-plate *h* is supported and rotates upon the same center as the cylinder *g*. The cam-face *h'* engages with and operates the truck *e*, bolt *c*, and carrier *f*, and the cam-face *h²* engages with and operates the truck *m⁵*, lever *m*, and shear-blade *n*. The extent of the cam-faces *h'* and *h²* round portions of the cam-plate depends upon the extent to which the thickening is required to be applied to the material, usually about half the circumference. *i*, Fig. 7, is a catch pivoted at *i'* to a lug or bracket *i²*, formed in one with the cam-plate *h*. *i'*, Fig. 2, is a notch in the rim of the cylinder for receiving the catch *i*. *b* is a part of the stationary frame. It will thus be understood that the cylinder *g* and cam-plate *h* rotate together when the catch *i* is in the notch *i'* of the cylinder, as shown in Fig. 7, and that when the catch *i* is out of the notch *i'*, as shown in Fig. 2, the cam-plate *h* remains stationary. My additional mechanism is then disconnected and ordinary knitting only is effected by the machine. *k* is a spring formed and fitted so as to retain the catch *i* in the locked or unlocked position. *o* is the curved cloth-presser. *p* is the looper-wheel, and *r* is the sinker-wheel.

Referring to Figs. 1, 6, 8, 9, and 10, *m* is a curved lever pivoted at *m'* to the bracket *m⁶*, the bracket being firmly bolted to the bed-

plate *b*. The lower end of the lever *m* is fitted with the roller-truck *m*⁵, the roller of which is alternately kept in contact with the cam-plate *h* and raised cam-surface *h*² by the spring *m*³, attached to the pin *m*³ on the lever *m*, and to the stationary pin *m*⁴, fixed to the stem of the presser-wheel *s*. The lever *m* is caused to oscillate upon its center *m'* by the contact of the truck *m*⁵, rolling upon the normal and raised surfaces of the cam *h* and *h*². The upper end of the lever *m* is formed as a fork *m*⁷ to receive the end of the shear-blade *n*, whereby the shear-blade is caused to cut the thread at the proper moment. The shear-blade *n* is pivoted to the lower end of the bolt *n*⁵, and is held down in position by the spring *n*³. *n*² is a small lever pivoted to the pillar *n*⁷ and pressed downward by the spring *n*⁴, attached to the bolt *n*⁵. *n*⁶ is a small plate attached to the shear-blade *n*, having an inclined surface for lifting the lever *n*² when the shear-blade revolves on the bolt *n*⁵. The blade *n* and lever *n*² co-operates with a fixed shear-blade *n*⁸ to sever and to hold down the thread. *u*, Fig. 9, is the ordinary knitting-thread, and *t* is the guide for the same, guiding the thread *u* to the looper-wheel *p*. The end of the guide *t* is provided with a hook *t'*, which carries the ordinary thread *u* and receives the additional thread *v*, Fig. 3, when lowered by the carrier *f*. When the additional thread *v* is again raised by the carrier *f*, the ordinary thread *u* is prevented from rising therewith by the stud *t*². It will be understood that when the carrier *f* is raised the additional thread *v* is thereby raised out of the hook *t'* above and clear of the looper-wheel *p*. This looper-wheel has one of its wings formed with a projection, as shown at *p'* in Fig. 10. The operation is as follows: When the carrier *f* is lowered, the additional thread *v* is thereby carried down into the hook *t'* of the ordinary thread - guide *t*. This movement causes the specially-shaped wing *p'* of the looper-wheel *p* to seize the additional thread *v* and carry it to the needles with the ordinary thread *u*. At the same moment the shear-blade *n* is withdrawn from contact with the lever *n*² by the operation of the fork *m*⁷ of the lever *m*. The lever *n*² is lifted by the plate *n*⁶, attached to *n*, whereby the additional thread *v* is released from the lever *n*² and permitted to travel with the thread *u* to the needles. When the cam-plate *h* has revolved and carried the raised portion of the cam *h'* beyond the range of the truck *e*, the

latter ascends and allows the bolt *c* to raise the carrier *f*. The additional thread *v* is thereby withdrawn from the hook *t'*. At the same time the cam-plate *h* has revolved and carried the raised portion of the cam *h*² beyond the range of the truck *m*⁵, whereby the fork *m*⁷ has returned the shear-blade *n* to the position shown in Fig. 8, the lever *n*⁶ falls upon and secures the end of the additional thread, and the shear-blade *n* at the same time severs its connection with the fabric. The additional thread is then held stationary until the cams *h'* and *h*² on the cam-plate *h* again come round to the trucks *e* and *m*⁵ and repeat the operation. By these means the additional thread is seized at the proper instant, added to the fabric for thickening, then cut off, secured, and held ready for the next operation of thickening. 75

I claim--

1. In a circular-knitting machine, the combination of the needle-cylinder *g*, having notch *i'*, the cam-plate *h*, provided with bracket *i*², and the catch *i*, pivoted to said bracket, substantially as and for the purpose described. 80

2. The combination of the cam-plate *h*, the vertically-reciprocating bolt *c*, provided with roller-truck *e* and spring *d*, and the carrier *f* for carrying the additional thread for splicing and thickening, substantially as described. 85

3. The combination of the cam-plate *h*, the lever *m*, provided with roller-truck *m*⁵, spring *m*³, and fork *m*⁷, the shear-blade *n*, the fixed shear-blade, and the lever *n*², substantially as described. 90

4. The combination of the guide *t*, having hook *t'* and stud *t*², for receiving and guiding the ordinary thread, the carrier *f* for carrying the additional thread, and means for actuating the carrier, substantially as described. 95

5. The combination, with the looper-wheel *p*, having wings, one of which is provided with a projection *p'* for the purpose of seizing the additional thread, of the carrier *f* for carrying said additional thread, and actuating means for said carrier, substantially as described. 100

6. The herein-described looper-wheel having a wing provided with projection *p'*, substantially as and for the purpose set forth.

JAMES BETTNEY.
